UNITED STATES PATENT OFFICE.

JOHN L. FATE, OF CHICAGO, ILLINOIS, ASSIGNOR TO AMERICAN INSULATING COMPANY, A CORPORATION OF MAINE.

SEALING-NIPPLE FOR VACUUM-JACKETS.

No. 926,694.

Specification of Letters Patent.

Patented June 29, 1909.

Application filed July 25, 1907. Serial No. 385,547.

To all whom it may concern:

Be it known that I, JOHN L. FATE, a citizen of the United States, residing at Chicago, in the county of Cook and State of Illinois, have invented a certain new and useful Improvement in Sealing-Nipples for Vacuum-Jackets, of which the following is a specification.

A number of sealing nipples have been invented for this purpose. The ones with which I am familiar are subject to the objection that there is always more or less of a loss of the vacuum during the operation of closing the seal.

My invention has for its object to provide an effective means for sealing vacuum jackets; and to this end the same consists of the novel devices and combinations of devices hereinafter described and defined in the claims.

In the broad point of view, my invention is within the principles disclosed in my earlier filed pending case S. N. 318,639, filed May 25, 1906 and is covered by the generic claims therein contained. It is, however, a material improvement over the form of structure disclosed in my said earlier case.

The invention is illustrated in the accompanying drawing wherein the single view is a vertical sectional elevation through a vacuum jacket equipped with my improved form of sealing nipple.

In the said drawing, the numeral 1 represents a hollow body adapted, when the air is exhausted therefrom, to afford a vacuum chamber 2.

The numeral 3 represents my improved sealing nipple. This nipple is seated in one wall of the jacket 1 and, as shown, has a flange 4 which is brazed to the wall of the jacket for rigidly connecting the nipple thereto with an air tight joint. The nipple is of such size and shape that it has a portion located within the chamber 2 of the jacket 1 and an external portion projecting outward above the wall in which the nipple is seated; and that portion of the nipple within the chamber 2, as shown, is shaped to afford a sealing trap 3^a and the nipple is contracted at the junction of this trap portion thereof with the external or projecting part of the nipple. This contraction is sufficient to enable the external projecting portion of the nipple to hold particles of solder or other

fusible metal 5, through which the air can be drawn by the exhausting pump.

The numeral 6 represents a section of flexible hose or pipe leading to an exhausting pump not shown. The exhausting pump is assumed to have a valve or stop cock intermediate its barrel and the hose or pipe section 6, which valve can be closed without the removal of the pump for maintaining a vacuum on both sides of the fusible material 5.

Under the action of the pump the air is exhausted from the chamber 2 and the nipple 3, as the pellets of fusible material readily permit the air to pass therethrough. After the vacuum has been made as nearly perfect as can be done under the action of the pump, the stop cock or valve at the pump is turned into its closed position, so as to prevent the back flow of any air from the atmosphere through the hose 6 and the nipple 3 to the vacuum chamber 2. Then heat is applied to that portion of the nipple 3 containing the pellets of fusible material 5, while the vacuum is maintained on both sides thereof, and the fused material will run down, into the trap portion 3^a of the nipple and there solidify, as shown by the dotted lines in the drawing; and as soon as this occurs the vacuum chamber will be hermetically sealed. Then the protruding part of the nipple is cut off close to the wall of the jacket and may, if desired, be covered by a shield. The vacuum jacket is then ready for use.

In the drawing the full lines show the fusible material 5 as located when in the form of pellets or small particles, through which the air can be drawn under action of the pump, and the dotted lines show this fusible material 5 as it becomes solidified in the trap portion 3^a of the nipple after it has been fused under the application of heat to the projecting portion of the nipple containing the fusible material in pellet form. The heat for this purpose can conveniently be applied by an ordinary blow pipe. The fusible material 5 may be ordinary solder or any other metal having a lower fusibility than the metallic nipple 3.

It, perhaps, should be noted that when the nipple is made of the form and applied as illustrated and described, there is no projecting portion left outside the external surface of the jacket wall after the sealing is

completed and the projecting end of the nipple is cut off. This is an advantage because it avoids the danger of cracking the solder or breaking the joint at the place where the nipple is seated in the wall of the jacket.

The method of sealing herein disclosed is not claimed herein, but is made the subject matter of another application.

10 What I claim is as follows:

1. The combination with a hollow body adapted to afford a vacuum jacket when the air is exhausted therefrom, of an air exhausting and sealing nipple seated in one wall of said jacket adapted to be loaded with fusible material through which the air can be pumped and which nipple is shaped to afford a sealing trap into which said fusible material will flow and solidify after being fused within the nipple while the vacuum is

maintained on both sides thereof, thereby hermetically sealing the vacuum jacket, substantially as described.

2. The combination with a hollow body adapted to afford a vacuum jacket when the air is exhausted therefrom, of an air exhausting sealing nipple seated in one wall of said jacket adapted to be loaded with fusible material through which the air can be pumped, and which nipple is shaped to afford a sealing trap into which said material will flow when fused and operate to seal the vacuum jacket and which nipple has its trap portion located within the vacuum chamber, substantially as described.

JOHN L. FATE.
